STONE MUCKING MACHINE

Peter Yannes, Hazleton, Pa.

Application October 9, 1935, Serial No. 44,150

18 Claims. (Cl. 198—14)

This invention relates to new and useful improvements in a stone mucking machine.

The invention has for an object the construction of a device as mentioned which is adapted to be placed within the tunnel of a mine and collect material from the tunnel to the front of it, and discharge this material within a mine car.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a side elevational view of a device constructed according to this invention shown positioned within the tunnel of a mine.

Fig. 2 is a plan view of Fig. 1 looking in the direction of the line 2—2 thereof.

Fig. 3 is a fragmentary enlarged detailed view of a portion of Fig. 1.

Fig. 4 is a plan view of Fig. 3.

Fig. 5 is a sectional view taken on the line 5—5 of Fig. 4.

Fig. 6 is a view similar to Fig. 5 but illustrating the parts in a different position.

Fig. 7 is a sectional view taken on the line 7—7 of Fig. 5.

Fig. 8 is a detailed view of the inner end of one of the cables to show its relation to a reversing mechanism.

Fig. 9 is a fragmentary enlarged detailed view of a portion of Fig. 2.

Fig. 10 is a view similar to Fig. 9 but illustrating the device in a different position.

Fig. 11 is another view similar to Fig. 9 but illustrating the device in another position.

Fig. 12 is a sectional view taken on the line 12—12 of Fig. 9.

Fig. 13 is a sectional view taken on the line 13—13 of Fig. 1.

Fig. 14 is a sectional view taken on the line 14—14 of Fig. 1.

The stone mucking machine, according to this invention, comprises a carriage consisting of a platform 10, a frame 11, and a reinforcement structural strut 12. The platform 10 is supported upon wheels 13 which engage tracks 14 laid upon the floor 15 of a tunnel 16 of a mine. A trough 17 is supported upon the frame 11 and connects with a continuation trough 18 supported upon the structural strut 12. The trough 17 is pivotally mounted by a pintle 19 so that it may be pivoted to an inoperative position, as indi-

cated by the dot and dash lines 17'. In this latter position it rests upon the frame 11. In the operative position the trough 17 extends from the ground at the front to the trough 18. A mine car 20, also adapted to run on the tracks 14, is connected with the platform 10 and is located beneath the trough 18 so that the stone muck may be discharged therein.

A pusher cart 21 is located within the front end of the trough 17. A relay pusher cart 22 is located in the top horizontal trough 18 and is associated with mechanism by which all stone muck delivered by the pusher cart 21 may be pushed along as hereinafter further described.

A mechanical scoop is provided for lifting the stone muck into the front end of the trough 17. This mechanical scoop consists of a scoop 23 which has a leading edge 24 for engaging the ground and which has a handle 25 extended from the top thereof. The handle 25 is provided with a pulley 26 beneath which a cable 27 passes. This cable is attached at one end 28 upon the side of the trough 17. The other end of the cable is guided by pulleys 29 mounted on the trough opposite the end 28 and connects with a drum 30 upon one end of the shaft of a motor 31. On the other end of the motor shaft there is another drum 32 upon which there is wound one end of a cable 33. This cable 33 extends over guide pulleys 34 mounted on the trough 17, and over a pulley 35 on the end wall of the tunnel 16.

A clutch is associated with the motor 31 and comprises a handle 36 pivotally mounted at one end and connected with an operator rod 37 controlling the clutch jaws 38 and 38'. The arrangement is such that when one clutch jaw is engaged, the other one is disengaged. Thus, the rotations from the motor 31 are transmitted to one or the other of the drums. (The details of the clutch will not be given in this specification since they form no part of the invention.) When the drum 30 rotates, the scoop 23 will be drawn towards the trough 17, and when the drum 32 rotates the scoop will be drawn back to the ground.

The front end of the trough 17 is provided with an inclined plank 39 along which the stone muck may be forced by the scoop 23 until the scoop has reached a position indicated by the dot and dash lines 23' in Fig. 3. In this latter position all the material to the front of the scoop will have been discharged into the trough 17.

A mechanism is provided for moving the pusher car 21 up the trough 17 to discharge said material on the relay pusher cart 22, and after

it reaches the top, returning automatically to its original position. This mechanism consists of an electric motor 40 which is mounted on the platform 10 and which has cranks 41 attached 5 on the shaft thereof. These cranks 41 are connected by connecting rods 42 to a pair of triangular plates 43 which are pivotally supported at their centers 44 on the sides of the trough 17 with the rods 44'. Cables 46 and 46' are attached 10 on the top and bottom ends of the plate 43 and extend over pulleys 47 which are mounted by rods 47' on the sides of the trough. These cables connect at their ends with vertical strips 49 pivotally mounted at their centers upon support rods 50. The arrangement is such that rotations from the motor 40 will cause the cables 46 and 46' to oscillate forwards and rearwards. There is a duplicate mechanism on each side of the trough, as clearly shown in Figs. 2, 4, etc. 15

At each side of the trough 17 there is a vertical shaft 51 upon which there is mounted a dual drum comprising sections 52 and 53. A cable 54 is wound on the drum section 52 and extends over guide pulleys 55 and is attached to 20 the back side of the pusher cart 21. A cable 56 is wound upon the drum section 53 and extends over guiding pulleys 57 and is connected to the front of the pusher cart 21. The guiding pulleys of the cables are so arranged that when the shaft 25 51 is turned in one direction, the pusher cart will be moved forwards, and when turned in the opposite direction, it will move rearwards. The cables and the guiding pulleys are so arranged that the pusher cart 21 may travel upwards upon 30 the trough 17 to a position, indicated by the full lines in Fig. 5, in which it discharges on the horizontal relay pusher cart 22.

There is a gear 59 secured upon each end of the shafts 51. This gear is adapted to be engaged by a ratchet operated by the oscillating cables 46 and 46' to cause the shaft to rotate in one direction or the other, depending upon the adjustment of a control. More particularly, in Fig. 9 the control is shown in detail arranged 35 in a neutral position, one in which the oscillations are not transmitted. The transmitting device consists of a block fixedly mounted upon the oscillating cable and carrying a triangular shaped pawl 61 which is pivotally mounted at the point 62. The apex of the pawl 61 engages 40 against a spherical member 63 urged into operative position by a spring 64. The spherical member 63 is arranged upon the end of a plunger 65 slidable in a standard 66 on the block 60. A control pawl 67 is pivotally mounted intermediate 45 of its ends by a pawl 68 and arranged in a manner so that its forward end is adapted to engage a shoulder 69 upon the pawl 61 to hold the pawl in the neutral position. A cable 70 connects with 50 the pawl 67 to pivot the pawl to an inoperative position. A spring 71 urges the pawl 67 into the 55 operative position.

The cables 70, from each of the pawls 67, connect with cables 72 connecting with a control lever 73. Thus, when the control lever 73 is pivoted manually the pawls 67 are moved to the inoperative position. In the inoperative (the lower position) of the pawl 67 the pawl 61 will automatically pivot to the forward position indicated in Fig. 10. Carried on the pawls 61 there are two-way ratchets 75 urged into operative positions by a spring 76. These ratchets are equipped with projecting pins 77 engaged by the edges of the pawl 61. Thus when the pawl is 60 pivoted to the forward position, as shown in Fig. 75

10, one of the ratchets 75 will be lifted to an inoperative position, while the other ratchet 75 will be urged by the spring 76 into operative position.

Oscillations of the cables (46 and 46') will now 5 be transmitted by the engaged ratchet to rotate the gears 59 and thus the shafts 51. The shafts 51 are now turning so as to wind the cable 56 on the drum 53 to move the pusher cart 21 forwards. The cable 54 is now unwinding from the 10 drum section 52. The pusher cart 21 will move slowly forwards and advance all of the material in the trough 17 to the front of it.

The pusher cart 21 comprises a frame having a plate on the front thereof, and at the rear provided with rollers 78. The cables 54 are connected to the cart in the vicinity of the rollers 78 as clearly shown in Fig. 5. It is thus possible for the pusher cart to assume the position shown in Fig. 5 in which the material is completely 20 discharged on the relay pusher cart 22.

The pawls 61 at the top and at the bottom of each of the shafts 51 are connected for unitary motion by a wire frame 79 and 79'. This wire frame has eye portions 80 through which the 25 cables 54 and 56 pass. Stops 81 (see Fig. 8) are attached on the cables near the inner ends thereof and are adapted to engage against the ends of springs 82 mounted on the cables adjacent the eye portions. It is thus possible to simultaneously pivot the pawls 61 for automatically reversing the forward motion of the pusher cart, as hereinafter further described.

From the position of the pawl 61 shown in Fig. 10, which is the position in which the pusher cart is moving forwards, the pawls will be pivoted to the position shown in Fig. 11 by the action of the stops 81. More particularly, when the pusher cart 21 has reached the position shown in Fig. 5, the stops 81 on the unwound cable will operate 40 the frame of the pawls and pivot the pawls.

The pawls will be retained in the new position by the action of the spherical member 63 and the spring 64. In the new pivoted position of each pawl 61 the ratchets 75, which were peripherally engaged with the gears 59 will be out of engagement, and the previously inoperative ratchets placed into engagement. The oscillation of the cables 46 and 46' will now be transmitted to rotate the shaft 51 in the opposite direction. This causes the pusher cart to move rearwards. When the pusher cart has reached the complete rear position, that is, the initial position shown in Fig. 3, one of the stops 81 will again engage the frames 79 of the pawls 61 and pivot 55 the pawls to the neutral or initial positions illustrated in Fig. 9. The operation of the pusher cart is now at an end and will not be resumed, except if the lever 73 is again manually operated.

The pusher cart 22 is very similar in construction to the pusher cart 21 and is operated by mechanism very similar to the mechanism operating the pusher cart 21. More particularly, cables 46^a and 46^b are connected with the pivoted members 59 and are extended along the sides of the trough 18 and are connected with other pivoted members 83. The arrangement is such that the oscillating of the cables 46 and 46' are directly transmitted to the cables 46^a and 46^b. Vertical shafts 84 are mounted upon the sides of the trough 18 and support drums 85 and 86. Cables 87 are mounted on the drums 85 and extend over guiding rollers 88 and connect with the spindles 75

89 of the rollers 90 of the frame 91 of the pusher cart 22.

Another cable 92 connects with the spindles 89 and extends over guiding pulleys 93, 93', etc., and are wound upon the drums 86. The arrangement is such that when the shaft 84 is turned in one direction, the relay pusher cart 22 will be moved forwards from its initial position which is illustrated in Fig. 5. When the shafts 84 are turned 10 in the opposite direction, the pusher cart 22 will move rearwards until it has reached the initial position which is shown in Fig. 5. The mechanism for turning the shafts 85 in one direction or the other is identical to the mechanism used 15 in turning the shafts 51. This mechanism is clearly shown in Figs. 3 and 4 and the corresponding parts thereof may be recognized by the same reference numerals.

The pawls 61 of the second shaft turning mechanism are connected by frames 79^a, which frames are provided with eye members 80^a. The cables 87 and 92 respectively pass through these eye members for automatically operating the pawls as previously described. An automatic device is 20 provided for moving the pawls 61 of the second shaft operating mechanism to the forward operating position and consists of a cable 95 which is connected with the pawls 67 of the second shaft operating mechanism. These cables 95 are 25 extended over guiding pulleys 96 and terminate through guiding blocks 97 at which points they are connected with springs 98 connected with the free ends of levers 99. These levers are pivotally mounted and have their extremities engaging over and in the vicinity of the cables 56. Thus, when the stops 81 of the cables 56 operate 30 the pawls of the first mechanism to reverse the travel of the pusher cart, the levers 99 will be simultaneously operated by the stops 81 to set 35 the pawls 61 of the second mechanism into forward operation. Then, as the pusher cart 21 returns to its initial positions, the pusher cart 22 will be moved forwards to relay the movement of the material to the train car 20.

40 The trough 17 may be pivoted to the horizontal position, indicated by the dot and dash lines, by the operation of a lazy tong structure shown in Figs. 1 and 2. This lazy tong structure includes several relays 100 pivotally connected with a stationary frame and with the trough, and operated by a screw shaft 101. This screw shaft is provided with a handle 102 by which it may be rotated. The screw shaft 101 has right and left hand threads on sections thereof. When the handle 102 is turned the arms 100 of the lazy tong structure will be spread to collapse the structure, or may be contracted to extend the structure. Thus, it is possible to move the rear end 45 of the trough 17 upwards or downwards. The car 20 may have any number of traps in the top thereof through which the material which is advanced by the relay pusher carts may be discharged. The top trough 17 may continue horizontally through any distance so that the material 50 may be discharged to other trains upon the track 14.

The operation of the device is as follows:—The scoop 23 is operated to move forwards and force the material from the ground of the mine tunnel 55 up the incline 39 of the trough 17 into the trough and to the front of the pusher cart 21. The scoop 23 may move forwards or rearwards by proper operation of the clutch system of the motor 31. When sufficient material has been discharged into 60 the trough the pusher cart 21 is set into operation

by moving the lever 73. This causes the pawls 61 of the first pusher cart mechanism to move to the forward positions, as shown in full lines in Fig. 10.

The motor 40 is continually operating to pivot 5 the plates 43 and cause the cables 46, 46' and 46^a and 46^b to be continually oscillating. In the forward position of the pawl 61 the oscillations of the cables will be transmitted to rotate the shafts 51 and cause the pusher cart 21 to slowly move up 10 the trough 17. When the pusher cart has reached the complete top position shown in Fig. 5, it will have discharged all of its material on the pusher cart 22. In this position the stops 81 cause the pivoting of the pawls 61 to the backward position shown in Fig. 11. This automatically causes the pusher cart 21 to start moving 15 rearwards. Simultaneously, with the reversing of the pusher cart 21, the pusher cart 22 is set into operation by the stops 81 engaging the levers 99. The pusher cart 22 will now start advancing and relay the forward motion of the material discharged by the pusher cart 21. In Fig. 6, the pusher cart 22 is shown in an advanced position. When the pusher cart 22 reaches the fully 20 advanced position it will be reversed in its travel by the automatic operation of the pawls 61 of the relay pusher cart mechanism. It will then return to its original position. There are hooks 105 on the trough 18 in the vicinity of the rearward position of the pusher cart 22 to assist the pusher cart in pivoting into the closed position shown in Fig. 5. These hooks 105 are counter-weighted by weights 106 so as to act automatically. 25

30 While I have illustrated and described the preferred embodiment of my invention, it is to be understood that I do not limit myself to the precise construction herein disclosed and the right is reserved to all changes and modifications coming within the scope of the invention as defined in the appended claims.

35 Having thus described my invention, what I claim as new, and desire to secure by United States Letters Patent is:—

40 1. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, and a mechanism for moving the relay pusher cart along the trough to discharge the material into a receiving device and thereafter returning it to its original position.

45 2. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said 50 trough, a mechanism for moving said pusher cart up said trough to discharge said material on said relay pusher cart and after it reaches the top returning it to its original position, and a mechanism for moving the relay pusher cart along the 55 trough to discharge the material into a receiving device and thereafter returning it to its original position.

60 3. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said 65 trough, a mechanism for moving said pusher cart up said trough to discharge said material on said relay pusher cart and after it reaches the top returning it to its original position, and a mechanism for moving the relay pusher cart along the 70 trough to discharge the material into a receiving device and thereafter returning it to its original position.

- trough to discharge the material into a receiving device and thereafter returning it to its original position, said carriage comprising a platform mounted on rollers engaging a track, a frame 5 mounted on said platform to which the said inclined portion of the trough is pivotally mounted, and a structural brace from the platform supporting the said top horizontal portion of the trough.
10. 3. A stone mucking machine, comprising a carriage, a trough supported on the carriage and having a front upward inclined portion connecting with a top horizontal portion, a pusher cart in the front end of said trough, a relay pusher 15 cart in the top horizontal portion of the trough and in the base wall thereof, a mechanical scoop for lifting ground material into the front of said trough, a mechanism for moving said pusher cart up said trough to discharge said material on said 20 relay pusher cart and after it reaches the top returning it to its original position, and a mechanism for moving the relay pusher cart along the trough to discharge the material into a receiving device and thereafter returning it to its original 25 position, the front end of the trough having an inclined surface up which said scoop may travel, and an open top into which the material may discharge.
30. 4. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in 35 the base wall thereof, a mechanical scoop for lifting ground material into the front of said trough, a mechanism for moving said pusher cart up said trough to discharge said material on said relay pusher cart and after it reaches the top returning it to its original position, and a mechanism for moving the relay pusher cart along the trough to discharge the material into a receiving device and thereafter returning it to its original 40 position, said carriage comprising a platform mounted on rollers engaging a track, a frame 45 mounted on said platform to which the said trough is pivotally mounted, and a structural brace from the platform supporting the said top horizontal portion of the trough, and means for holding the front portion of the trough in the inclined position.
50. 5. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said 55 trough, a mechanism for moving said pusher cart up said trough to discharge said material on said relay pusher cart and after it reaches the top returning it to its original position, and a mechanism for moving the relay pusher cart along the trough to discharge the material into a receiving device and thereafter returning it to its original 60 position, said carriage comprising a platform mounted on rollers engaging a track, a frame 65 mounted on said platform to which the said trough is pivotally mounted, and a structural brace from the platform supporting the said top horizontal portion of the trough, and means for holding the front portion of the trough in the inclined position, comprising a

lazy tong structure extensible and retractable by the operation of a screw.

6. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material 10 into the front of said trough, a mechanism for moving said pusher cart up said trough to discharge said material on said relay pusher cart and after it reaches the top returning it to its original position, and a mechanism for moving 15 the relay pusher cart along the trough to discharge the material into a receiving device and thereafter returning it to its original position, said mechanical scoop comprising a motor operating a right or a left drum to which there is a 20 fore and an aft cable connected with the front and rear of said scoop.

7. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said 25 trough, a mechanism for moving said pusher cart up said trough to discharge said material on said relay pusher cart and after it reaches the top returning it to its original position, and a mechanism for moving the relay pusher cart along the trough to discharge the material into a receiving device and thereafter returning it to its original 30 position, said mechanical scoop comprising a motor operating a right or a left drum to which there is a fore and an aft cable connected with the front and rear of said scoop, 35 said cables being guided over pulleys mounted upon the trough and mounted upon the wall of said mine.

8. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said 45 trough, a mechanism for moving said pusher cart up said trough to discharge said material on said relay pusher cart and after it reaches the top returning it to its original position, and a mechanism for moving the relay pusher cart along the trough to discharge the material into a receiving device and thereafter returning it to its original 50 position, said mechanism for moving the pusher cart comprising dual drums rotatively mounted at the sides of the trough, a fore cable attached on said pusher cart and extending over guiding pulleys and wound upon one of the drum sections, an aft cable attached on the 55 pusher cart and extending over guiding pulleys and wound upon the other of said drum sections, gears fixed on shafts of said drums, adjustably mounted pawls supporting two-way ratchets 60 co-actable with said gears, means for oscillating the ratchet structure to rotate the drums, means for holding the pawls to hold the ratchets so that the pusher cart moves forwards, and automatic means for moving said walls to reverse the 65 70

ratchet action to move the pusher cart back to its original position.

9. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, and a mechanism for moving the pusher cart comprising dual drums rotatively mounted at the sides of the trough, a fore cable attached on said pusher cart and extending over guiding pulleys and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forwards, and automatic means for moving said pawls to reverse the ratchet action to move the pusher cart back to its original position, said means holding the pawls comprising resilient means engaging apex portions of the pawls substantially as described.

10. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, and a mechanism for moving the relay pusher cart along the trough to discharge the material into a receiving device and thereafter returning it to its original position, said mechanism for moving the pusher cart comprising dual drums rotatively mounted at the side of the trough, a fore cable attached on said pusher cart and extending over guiding pulleys and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forwards, and automatic means for moving said pawls to reverse the ratchet action to move the pusher cart back to its original position, said means holding the pawls comprising resilient means urging against one of the apexes thereof to urge the pawls into one position and to hold the pawls in said or in another pivoted position.

11. A stone mucking machine, comprising a carriage, a trough supported on the carriage and having a front upward inclined portion connect-

ing with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, and a mechanism for moving the relay pusher cart along the trough to discharge the material into a receiving device and thereafter returning it to its original position, said mechanism for moving the pusher cart comprising dual drums rotatively mounted at the sides of the trough, a fore cable attached on said pusher cart and extending over guiding pulleys and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forwards, and automatic means for moving said pawls to reverse the ratchet action to move the pusher cart back to its original position, said means holding the pawls comprising resilient means engaging apex portions of the pawls substantially as described.

12. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, a mechanism for moving the relay pusher cart along the trough to discharge the material into a receiving device and thereafter returning it to its original position, said mechanism for moving the pusher cart comprising dual drums rotatively mounted at the sides of the trough, a fore cable attached on said pusher cart and extending over guiding pulleys and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forward, and automatic means for moving said pawls to reverse the ratchet action to move the pusher cart back to its original position, means for holding the said pawls in neutral positions so that the ratchets are in inoperative position.

13. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top

returning it to its original position, a mechanism for moving the relay pusher cart along the trough to discharge the material into a receiving device and thereafter returning it to its original position, said mechanism for moving the pusher cart comprising dual drums rotatively mounted at the sides of the trough, a fore cable attached on said pusher cart and extending over guiding pulleys and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forward, and automatic means for moving said pawls to reverse the ratchet action to move the pusher cart back to its original position, means for holding the said pawls in neutral positions so that the ratchets are in inoperative position, means for automatically moving the ratchets to operative forward positions.

14. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, a mechanism for moving the relay pusher cart along the trough to discharge the material into a receiving device and thereafter returning it to its original position, said mechanism for moving the pusher cart comprising dual drums rotatively mounted at the sides of the trough, a fore cable attached on said pusher cart and extending over guiding pulleys and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forward and automatic means for moving said pawls to reverse the ratchet action to move the pusher cart back to its original position, means for holding the said pawls in neutral positions so that the ratchets are in inoperative position, means for automatically moving the ratchets to operative forward positions, including cables operating holding auxiliary pawls engaging said pawls, said cables being connected with hand levers.

15. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, a mechanism

for moving the relay pusher cart along the trough to discharge the material into a receiving device and thereafter returning it to its original position, said mechanism for moving the pusher cart comprising dual drums rotatively mounted at the sides of the trough, a fore cable attached on said pusher cart and extending over guiding pulleys and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forwards, and automatic means for moving said pawls to reverse the ratchet action to move the pusher cart back to its original position, means for holding the said pawls in neutral positions so that the ratchets are in inoperative position, means for automatically moving the ratchets to operative forward positions, including cables operating holding auxiliary pawls engaging said pawls, said cables being connected with hand levers, and means for automatically moving said pawls to reverse the travel of said pusher cart.

16. A stone mucking machine, comprising a carriage, a trough supported on the carriage and having a front upward inclined portion connecting with a top horizontal portion, a pusher cart in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart after it reaches the top returning it to its original position, a mechanism for moving the relay pusher cart along the trough to discharge the material into a receiving device and thereafter returning it to its original position, said mechanism for moving the pusher cart comprising dual drums rotatively mounted at the sides of the trough, a fore cable attached on said pusher cart and extending over guiding pulleys and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forwards, and automatic means for moving said pawls to reverse the ratchet action to move the pusher cart back to its original position, means for holding the said pawls in neutral positions so that the ratchets are in inoperative position, means for automatically moving the ratchets to operative forward positions, including cables operating holding auxiliary pawls engaging said pawls, said cables being connected with hand levers, and means for automatically moving said pawls to reverse the travel of said pusher cart, comprising stop elements upon the cables of the pusher cart and engageable with a frame structure connected with said portion.

17. A stone mucking machine, comprising a carriage, a trough supported on the carriage and having a front upward inclined portion connecting with a top horizontal portion, a pusher cart in the front end of said trough, a relay pusher

- cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, a mechanism for moving the relay pusher cart along the trough to discharge the material into a receiving device 10 and thereafter returning it to its original position, said mechanism for moving the pusher cart comprising dual drums rotatively mounted at the sides of the trough, a fore cable attached on said pusher cart and extending over guiding pulleys 15 and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forward, and automatic means for moving 20 said pawls to reverse the ratchet action to move the pusher cart back to its original position, said relay pusher cart being operated by mechanism substantially identical to the mechanism for operating said pusher cart. 25
- 30 18. A stone mucking machine, comprising a carriage, a trough supported on the carriage and having a front upward inclined portion connecting with a top horizontal portion, a pusher cart
- in the front end of said trough, a relay pusher cart in the top horizontal portion of the trough and in the base wall thereof, a mechanical scoop for lifting ground material into the front of said trough, a mechanism for moving said pusher cart up said trough to discharge said material on said relay pusher cart and after it reaches the top returning it to its original position, a mechanism for moving the relay pusher cart along the trough to discharge the material into a receiving device 10 and thereafter returning it to its original position, said mechanism for moving the pusher cart comprising dual drums rotatively mounted at the sides of the trough, a fore cable attached on said pusher cart and extending over guiding pulleys 15 and wound upon one of the drum sections, an aft cable attached on the pusher cart and extending over guiding pulleys and wound upon the other of said drum sections, gears fixed on shafts of said drums, adjustably mounted pawls supporting two-way ratchets coactable with said gears, means for oscillating the ratchet structure to rotate the drums, means for holding the pawls to hold the ratchets so that the pusher cart moves forward, and automatic means for moving 20 said pawls to reverse the ratchet action to move the pusher cart back to its original position, said relay pusher cart being operated by mechanism substantially identical to the mechanism for operating said pusher cart, 25 and automatically set into operation by stop elements on the cables of said pusher cart.

PETER YANNES.
